UNITED STATES PATENT OFFICE.

GEORGE H. ELLIS, OF CHICAGO, ILLINOIS, ASSIGNOR TO INTERNATIONAL HARVESTER COMPANY, A CORPORATION OF NEW JERSEY.

PITMAN CONNECTION.

SPECIFICATION forming part of Letters Patent No. 794,793, dated July 18, 1905.

Application filed February 18, 1905. Serial No. 246,210.

To all whom it may concern:

Be it known that I, GEORGE H. ELLIS, a citizen of the United States, residing at Chicago, in the county of Cook and State of Illinois, have invented certain new and useful Improvements in Pitman Connections, of which the following is a specification, reference being had to the accompanying drawings, forming a part thereof.

10 My invention relates to pitman connections, and is particularly applicable to the pump connections of oil or gas engines wherein the fluid is regularly forced from the source of supply to the carbureting mechanism by means of a force-pump operatively connected with a moving part of the engine.

In engines of the above class it is the usual practice to have the pump connections so arranged that the pump may be operated independent of the engine in order to supply sufficient explosive mixture to start the engine; and the object of my invention is to provide means that may be readily operated independently of the engine without affecting its normal operation; and it consists in providing a two-part pivotally-connected pitman connection between a moving part of the engine and the pump rod or plunger.

In the drawings, Figure 1 represents a side elevation of a portion of an engine sufficient to illustrate the application of my invention. Fig. 2 is a detail view of the pitman connection. Fig. 3 is a view showing the independent operation of the device. Fig. 4 is a side elevation, partly in section, of Fig. 2.

The same reference - numerals denote like parts.

5 is the engine-base; 6, the fly-wheel; 7, the crank-shaft; 8, the cylinder; 9, the valve-rod; 10, the pump; 11, the pipe connection from the pump to the supply-tank; 12, the pipe connection from the pump to the mixing-chamber; 13, the valve-operating gear-wheel driven by the gear 14, secured to the engine-shaft.

15 is a crank-wheel secured to the shaft

supporting the gear-wheel 13 and provided with a crank-pin 16.

17 is the plunger-rod of the pump and, 18 is a pitman connection between the plunger and the crank-pin 16.

50 The pitman comprises two parts 19 and 20, pivotally connected at 21 a short distance above the pivotal connection between the lower end of the pitman and the plunger 17. The upper portion of the pitman part 19 is 55 provided with a slotted opening 22, adapted to receive the inner end of a spring-actuated plunger-bolt 23, carried in a cylinder-like portion 24 at the upper end of the pitman part 20. The plunger-bolt 23 is provided with 60 a head 25 and a body portion 26, surrounded by a coil-spring 27, operative between the shoulder 28 on the bolt and the inner surface of the end of the cylinder, to project the inner end of the plunger-bolt into the slot in the 65 pitman part 19, as shown in Fig. 4.

When the plunger-bolt is in engagement with the slot, the two parts of the pitman operate as one piece during the regular operation of the engine. When it is desired to operate the pump by hand independent of the engine, the plunger-bolt is pulled out of the slotted opening in the part 19, and the part 20 may then be used in the same manner as an ordinary pump-handle, its fulcrum being 70 75 the joint-pin at 21, as shown in Fig. 3, by means of which the pump may be operated.

What I claim as my invention, and desire to secure by Letters Patent, is—

1. A pitman connection between a driving 80 and driven member comprising two overlapping members normally operating as one member, one end of the overlapping portion adapted to form a fulcrum upon which one part of the pitman may be moved in a manner to operate the driven member.

85 2. In a pitman connection between a driving and driven member, a pitman comprising two members pivotally connected one with the other and normally operating as one 90

member irrespective of their pivotal connection, and means for disengaging one member relative to the other whereby it may be rocked about the pivotal connection in a 5 manner to operate said driven member.

3. A pitman comprising two parts that are pivotally connected, a spring-bolt carried by one of the parts and adapted to engage with the other part in a manner to hold the two 10 parts normally operative.

4. A pitman comprising two parts that are pivotally connected, a cylindrical head formed upon one of the parts, a spring-actuated detent adapted to slide in the cylindrical 15 head in a manner to be engaged with or disengaged from the other part of the pitman.

5. In a pitman connection between a driving and driven member, the combination of a two-part pitman having one end of each part 20 pivotally connected with the driving and driven members, respectively, to normally operate as one part, and having the opposite

end of one of the parts pivotally connected with the other in a manner to form a fulcrum about which one part may be moved as a lever to operate the said driven member. 25

6. In a pitman connection between a driving and a driven member, the combination of a two-part pitman having one end of each part pivotally connected with the driving and driven members, respectively, to normally operate as one part and having the opposite end of one of the parts pivotally connected with the other in a manner to form a fulcrum about which one part may be moved 30 as a lever to operate the said driven member and means for releasably retaining the two parts in the normal operative position. 35

In witness whereof I hereto affix my signature in presence of two witnesses.

GEORGE H. ELLIS.
